FIG. 2

Des 225,104

PAGE 5

FIG. 3

FIG. 4

FIG. 1 is a perspective view showing my new design for a horse barn.

FIG. 2 is a top plan view thereof.

FIG. 3 is an end elevational view taken from the left of FIG. 2.

FIG. 4 is a perspective view similar to FIG. 1 showing a modified form of my new design for a horse barn.

The opposed ends of the lateral wings are identical with those shown in FIGS. 1 and 4. The opposed side of the central portion is identical with that shown in FIGS. 1 and 4.

I claim:

The ornamental design for a horse barn, as shown and described.
